CLAIM

The ornamental design for a door facing, as shown and described.

DESCRIPTION

FIG. 1 is a front perspective view of a first version of a door facing according to our design;

FIG. 2 is a front elevational view;

FIG. 3 is a front perspective view of a second version of a door facing according to our design;

FIG. 4 is a front elevational view;

FIG. 5 is a front perspective view of a third version of a door facing according to our design;

FIG. 6 is a front elevational;

FIG. 7 is a front perspective view of a fourth version of a door facing according to the second version of our design; and,

FIG. 8 is a front elevational view.

The evenly spaced broken lines depict portions of the door facing that form no part of the claimed design. The dot-dot-

(Continued)

dash broken lines depict the limits of the enlarged views and form no part of the claimed design.

1 Claim, 8 Drawing Sheets
